UNITED STATES PATENT OFFICE.

FREDERICK J. VAUX, OF LANCASTER, PENNSYLVANIA.

BOILER.

Application filed September 11, 1922. Serial No. 587,480.

This invention relates to boilers for generating steam, and is particularly directed to means for extracting a great amount of heat from the products of combustion before the same are finally expelled.

Another object of the invention is to provide an improved water circulating system.

With these and other objects in view which will be more apparent as the specification proceeds, the invention resides in certain novel features of construction, and combination and arrangement of parts, the essential elements of which are hereinafter fully described, are particularly pointed out in the appended claim, and are illustrated in the accompanying drawing, in which:

Fig. 1 is a front elevation of my improved boiler, parts being broken away for the sake of clearness.

Fig. 2 is a vertical, longitudinal sectional view of the same.

Like characters of reference refer to like parts in both views.

The views show the boiler in somewhat skeleton form, it being understood that the usual and suitable masonry is built about and encloses many of the parts to support the same, as is well known and understood in the art.

Referring to the drawing in detail, 10 and 11 represent steam and water drums and are provided with the usual water gages 12. These drums are also designed to receive the steam generated by the boiler and to deliver the same to the supply pipes which are shown at 13. The steam and water drums 10 and 11 are preferably cylindrical in form and arranged at opposite sides of the device and at the upper portion thereof as clearly shown in Fig. 1. A drum or boiler section 14 which I shall hereinafter refer to as the water front is arranged at the front of the device and may be supported in any suitable framework or masonry indicated generally at 15. The water front is connected by a pair of pipes 16 with the steam and water drums 10 and 11 as shown in Fig. 1 and as indicated in dotted lines in Fig. 2.

Similarly there is arranged at the rear of the structure and between the steam and water drums 10 and 11 a water back 17 which is connected by pipes 18 with the steam and water drums 10 and 11 at the rear. Supported in any suitable manner between the water front 14 and the water back 17 are a plurality of boiler sections 19, 20,

21, 22 and 23. It is of course understood that there may be a greater or less number of these boiler sections, but for the purpose of this description five will be sufficient to indicate the general scheme. The five boiler elements 19-23 are flat tanks extending completely across the space between the side walls so that none of the products of combustion can pass around the ends of these members directly to the smoke exit. The boiler elements or sections are relatively wide and are inclined forwardly and upwardly toward the water front, and are arranged at progressively decreased distances, 60 as the boiler elements or sections approach the rear of the boiler, and are also disposed in staggered relation one to the other to provide a continuous diagonal passage for the heating element. The lower portions of 65 members 19, 21 and 23 extend completely down to the floor or masonry so that no heat or smoke can pass under them while the members 20 and 22 extend completely to the roof of the masonry. In the operation, the 70 smoke and heat strike against the fire-brick 25 placed at the base of member 19 and is then conducted in a course indicated by the arrows in Fig. 2. The various elements 75 19-23 are arranged in a manner that the 80 cross-sectional area of the passage through which the products of combustion pass is such that there is an even, smooth and uninterrupted flow of the products of combustion. It is to be noted that in this manner 85 the hot air and gases pass over both of the major surfaces of every one of the elements 90 19 to 23.

As the boiler elements 20 and 22 pass out between steam and water drums 10 and 11 95 they are connected directly to the said steam and water drums 10 and 11 by pipes 26 and the members 19, 21 and 23 are connected by depending pipes 27. The final member 23 is connected by pipes 28 with the lower end of 100 the water back 17 and the lower portion of member 23 is connected by the pipes 29 to the rear ends of longitudinally arranged pipes 30 extending from front to rear of the device and connected at the front by risers 105 31 with the water front 14. The lower ends of the several members 19 to 22 are connected by respective pipes 32, 33, 34 and 35 with the respective pipes 30.

It will thus be seen that a complete thermo-siphon circulation of the water is capable from any one of the elements to any 110

other, and if one of the elements absorbs heat faster than another, thereby generating steam, this steam will be immediately passed into the steam and water drums 10 and 11 and the colder water from the other elements will be immediately circulated to this place. Therefore the greatest amount of heat will be extracted from the air and gas, and a complete circulation will be set up so as to maintain the water at a substantially uniform temperature.

While I have described what I deem to be the most desirable embodiment of my invention, I do not limit myself to the exact details of construction herein set forth, nor to anything less than the whole of my invention as set forth in the appended claim.

I claim:

In a boiler structure including a fire-box 20 therefor, the combination of a pair of horizontal interconnected drums parallel with the sides of the said structure outwardly of

and adjacent the top edge thereof, of front and rear substantially inverted L-shaped water backs, a plurality of boiler sections 25 relatively wide and inclining forwardly and upwardly toward the said water front, said boiler sections being at progressively decreasing distance as the sections approach the rear of the boiler, said sections disposed in staggered relation one to the other to provide a continuous diagonal passage for the heating element, the foremost portion of each of said sections being operatively connected to said drums and the back boiler 35 section being operatively connected adjacent the bottom end thereof to the side of the said water back, adjacent the bottom end therefore for effecting a thermo-siphon circulation in said boiler structure, the bottom portions 40 of said boiler sections being interconnected.

In testimony whereof I affix my signature.

FREDERICK J. VAUX.
